Primary Examiner—Ted Shooman*Assistant Examiner*—C Tuttle*Attorney, Agent, or Firm*—Donal B. Tobin; Edward S. Podszus; Aubrey C. Brine[57] **CLAIM**

The ornamental design for a razor cartridge, as shown and described.

DESCRIPTION

FIG. 1 is a top perspective view of a razor cartridge showing our new design;

FIG. 2 is a top plan view thereof;

FIG. 3 is a front elevational view thereof;

FIG. 4 is a rear elevational view thereof;

FIG. 5 is a bottom plan view thereof; and,

FIG. 6 is a right side elevational view thereof, the left side being a mirror image of the right side.

The broken lines showing the blades and underlying structure are for illustrative purposes only and do not constitute a part of the claimed design.

The appearance of the unshaded areas inside the solid line boundaries under the blades in FIG. 1, and inside the four oblong outlines in FIG. 5 forms no part of the claimed design.
